UNITED STATES PATENT OFFICE

2,492,853

LIFTING DEVICE

Robert C. Flynn, Houston, Tex.

Application October 23, 1945, Serial No. 623,996

1 Claim. (Cl. 254—126)

1

This invention relates to a lifting device and it is primarily an object of the invention to provide a device of this kind comprising a base member and a work-engaging member operatively connected by pivoted levers in a manner whereby the desired raising and lowering of the lifting member is effected upon rotation of an operating shaft.

Furthermore, it is an object of the invention to provide a device of this kind including a base member and a lifting member operatively connected by bars assembled as in a parallelogram and in a manner whereby, when the lifting member is at its maximum height, the parallelogram center lines will be in parallel, thereby forming two parallelograms at the highest point of the lifting member.

A still further object of the invention is to provide a device of this kind including a base member and a lifting member operatively connected by bars which form two parallelograms at the lowest point and when the lifting member is at its highest point but at no time forming a parallelogram within an action of the bars of 78 degrees.

An additional object of the invention is to provide a device of this kind comprising a base member and a lifting member operatively connected by two sets of bars in a manner whereby one set of bars forms a parallelogram below the horizontal center line and the second set of bars forms a parallelogram above the horizontal center line.

A still further object of the invention is to provide a device of this kind including a base member and a lifting member constructed and assembled in a manner wherein the action of the device is not that of a complete right angle but is variable between 12 degrees and 90 degrees off the horizontal center line.

The invention consists in the details of construction and in the combination and arrangement of the several parts of my improved lifting device whereby certain important advantages are attained as will be hereinafter more fully set forth.

In order that my invention may be better understood, I will now proceed to describe the same with reference to the accompanying drawings, wherein:

Figure 1 is a view in side elevation of a lifting device constructed in accordance with an embodiment of the invention and in its lowermost adjustment;

2

Figure 2 is a vertical sectional view showing the device in its uppermost adjustment;

Figure 3 is a view in end elevation of the device as illustrated in Figure 1;

Figure 4 is a fragmentary detail sectional view taken on the line 4—4 of Figure 2; and

Figure 5 is a fragmentary view partly in section and partly in top plan showing the engagement of the operating bar with the shaft.

10 In the embodiment of the invention as illustrated in the accompanying drawings, B denotes a base member and L a lifting member operatively connected in a manner whereby desired up and down movement of the lifting member L may be readily effected upon rotation of the heavy duty operating screw S.

The base member B includes a bottom plate 1 of desired dimensions and which is provided with the transversely spaced upstanding side plates 2

20 arranged in parallelism with each other and with the longitudinal axis of the plate 1. In the present embodiment of the invention, these plates 2 are equidistantly spaced at opposite sides of such longitudinal axis.

25 Pivots connected, as at 3 and 4, with the opposite end portions of each of the plates 2 are the inner extremities of the elongated bars 5 and 6 respectively. These bars 5 and 6 are arranged one above the other and the pivotal connections 4 of the upper bars 6 are disposed inwardly of the pivotal connections 3 of the lower bars 5.

It is also to be particularly pointed out that each set of pivotal connections 3 and 4 is of the same relative arrangement as all of the others. All of the bars 5 and 6 are of the same lengths and the outer extremities of each set of bars 5 and 6 are pivotally connected, as at 7, with a plate 8 welded to the side face of a knuckle block 9.

40 Freely disposed through one of the knuckle blocks 9 and threading through the other is an elongated heavy duty screw S whereby, upon requisite rotation of the screw S, the knuckle blocks 9 will be caused to move in unison either 45 one toward the other or in the opposite directions.

Keyed, as at 10, to an extended end portion of the screw S adjacent to the free knuckle block 9 is a tubular member or sleeve 11 projecting a desired distance beyond the adjacent end portion of the screw S. This extended portion is provided with an opening 12 diametrically opposed to the inner portion of an open slot 14 into which are adapted to be engaged a cross head 15 carried by an end portion of an elongated

operating bar 16 to be rotated in any manner desired, as by a hand crank.

Interposed between the inner end of the tubular member or sleeve 11 and the outer face of the adjacent knuckle block 9 is an antifriction assembly 17 which may be as desired.

Pivotedly connected at the upper point 7 with the plates 8 of the knuckle blocks 9 are the outer end portions of the lower top bars 18 which are disposed inwardly and upwardly and which have their inner extremities pivotedly connected, as at 19, with the lower portions of the transversely spaced plates 20 comprised in the lifting member L and depending from the top or work-engaging plate 21 of said lifting member L.

Directly above the pivotal mounting 7 for the lower bars 5 are pivotedly engaged, as at 21, the outer ends of the upper top bars 23 which are disposed substantially in parallelism with the bars 18 and have their inner extremities pivotedly connected, as at 24, with the plates 20 of the lifting member L outwardly of the pivots 19 and directly above the pivots 3 for the bars 5. The pivots 19 are directly above the pivots 4.

Upon proper turning of the screw S, the lifting member L will be raised and the extent of such upward movement will bring the bars 5, 6, 18 and 23 vertically in parallelism or with the bars 23 and 5 and the bars 6 and 18 in longitudinal alignment. The lowermost downward movement of the lifting member L is by contact of the bars 23 and 6 with the bars 18 and 5, respectively.

I claim:

A lifting device comprising a base member, a lifting member overlying the base member, an operating screw disposed horizontally between said members, knuckle blocks mounted for movement on and by the screw, bars pivotedly connected to and between the base member and the blocks and to and between the blocks and the lifting member, the bars being in two sets, the bars of one set being above the bars of the other

set, each set of bars consisting of two outside pairs and two inside pairs, each outside pair of bars having spaced ends between which a member is pivotedly joined, the opposite ends of each outside pair having a knuckle block therebetween, vertically spaced pivots on the knuckle blocks engaged by the said opposite ends of the outside bars of the upper and lower sets, the pivots for the spaced ends of one pair of bars and the pivots for the spaced ends of the bars joined to the same member being widely horizontally spaced and on opposite sides of the vertical center of the device, each inside pair of bars having spaced ends between which a member is pivotedly joined, the opposite ends of each inside pair having a knuckle block therebetween, pivots between each knuckle block and the said opposite ends of the inside pairs of bars adjacent thereto and forming a single axis transversely of the block on which the inside bars of the two sets turn, the pivots between the inside bars and the members adjacent thereto being set closer to the said vertical center of the device than the said widely spaced pivots, the pivots forming the single axes being set closer to the said vertical center of the device than the adjacent vertically spaced pivots to which the outside bars are connected, all of the bars of the sets being parallel when the lifting member is at the limit of its upward movement, and means for rotating the screw to move the blocks inwardly and outwardly.

ROBERT C. FLYNN.
